UNITED STATES PATENT OFFICE.

ELMER S. SHIMER, OF MILTON, PENNSYLVANIA.

PLATEN-SHIFT.

SPECIFICATION forming part of Letters Patent No. 701,095, dated May 27, 1902.

Application filed January 23, 1902. Serial No. 90,882. (No model.)

To all whom it may concern:

Be it known that I, ELMER S. SHIMER, a citizen of the United States, residing at Milton, in the county of Northumberland and State 5 of Pennsylvania, have invented new and useful Improvements in Platen-Shifts, of which the following is a specification.

My invention relates to improvements in platen-shifts; and one object of the same is 10 to construct a device of this character which will be adjustable for different fonts of type and be simple in construction and efficient in operation.

Another object is an adjustment of the basket to conform to the platen-shift adjustment.

The novel construction by which these objects are accomplished is fully described in this specification and claimed, and illustrated in the accompanying drawings, forming a 20 part thereof, in which—

Figure 1 is a side elevation with parts broken away. Fig. 2 is a perspective of a carriage with my platen-shift. Fig. 3 is a detail of one of the hangers and the catch. Fig. 4 25 is a detail of the V-shaped guide.

Like numerals of reference designate like parts in the different views of the drawings.

The numeral 1 designates the table of a standard form of type-writer frame, upon 30 which table the carriage 2 and its mechanism are mounted. The frame of the carriage comprises a front bar 3 and two side bars 4. A platen 5 is journaled in the side bars 4 and is held against all movement but that of rotation. In order to shift the platen to change 35 from lower to upper case type, it is necessary to move the whole carriage. To accomplish this in a simple manner, the side bars 4 are pivotally connected at their rear ends to the 40 upwardly-extending arms 6 of a rock-shaft 7. The rock-shaft 7 is supported in hangers 8, provided with hooks 9. Lugs 9^a are formed on the hooks 9 and serve as stops to limit the forward movement of the arms 6 when the 45 carriage is raised. Catches 10 serve to firmly secure the shaft 7 in place, but may be disengaged and the carriage readily detached when desired.

Means for actuating the carriage in shifting is provided in the shape of a movable

guide-bar 11, set parallel to the front bar 3 and bearing downwardly-extending arms 12, which extend through apertures 12^a in the table 1 and are pivoted on pins 13. One of the arms 12 bears a crank-arm 14, which extends at right angles thereto and is attached to the upper end of a connecting-rod 15, which is connected at its lower end to the bar 16 of a shift-key 17. A spring 13^a serves to return the bar 11 to its initial position. The bar 16 55 is pivoted at its rear end to adapt it to be operated in the usual manner.

Connection between the carriage 2 and the guide-bar 11 is made by a V-shaped guide 18, rigidly mounted on the bar 3 and sitting 60 astride the bar 11. The outer arm 18^a of the guide is sharpened to serve as an index for a scale 19, carried by the guide-bar 11.

It is necessary to vary the shift of the platen when employing different fonts of type, 70 and for that purpose adjustable stops 20 are located on each side of the arm 12 and comprise screws fitting threaded apertures 21^a in lugs 21, formed on a base-plate 22. This adjustment is never disturbed except when 75 changing the font of type or in taking up wear.

Since an adjustment of the platen-shift would also necessitate a corresponding adjustment of the basket to centralize the impinging stroke of the type, the type-bars 23 are pivoted to ears 24, all carried by a ring 25, which is supported by four legs 26, having slots therein engaged by bolts 27, rigidly mounted in apertures in cross-bars 28 across 80 the front and rear of the frame. By this arrangement the required adjustment is easily 85 made.

In operation the shifting-key 17 is held down when it is desired to print a capital. 90 This depression of the shift-key will throw the lever-arm 14, actuate the guide-bar 11, and operate the carriage to shift the platen.

It should be noted that to insure accuracy the lengths of the arms 6 and 12 should all be 95 the same and set so that the front of the carriage will be raised and the rear depressed an equal amount at each shift.

I do not wish to be limited as to details of construction, as these may be modified in 100

many particulars without departing from the spirit of my invention.

Having described my invention, what I claim as new, and wish to secure by Letters 5 Patent, is—

1. In a platen-shift, the combination with a carriage bearing a platen, of a rock-shaft bearing arms pivotally connected to said carriage, hangers bearing hooks engaging said 10 rock-shaft, catches for securing said rock-shaft in place, a shift-key and means for connecting said key to said carriage to shift said platen, substantially as described.

2. In a platen-shift, the combination with 15 a carriage, of guide-bar, a scale mounted on said guide-bar, and a V-shaped guide mounted on said carriage and embracing said guide-bar, one of the arms of said guide being

pointed to form an index for said scale, substantially as described. 20

3. In a platen-shift, the combination with a carriage-frame bearing a platen, four pivoted arms of equal length supporting said carriage-frame, said arms being so inclined that the fall of one side of the carriage is compensated by the rise of the other side so that the axis of the platen is in the same horizontal plane after the shift as it was initially, substantially as described. 25

In testimony whereof I have hereunto set 30 my hand in presence of two subscribing witnesses.

ELMER S. SHIMER.
